(57) **CLAIM**

The ornamental design for a storage device for electronic media, as shown and described.

DESCRIPTION

FIG. 1 is a perspective view;

FIG. 2 is a top view;

FIG. 3 is a bottom view;

FIG. 4 is a short side view; and,

FIG. 5 is a long side view.

The stippling that can be seen on the claimed design is a type of shading that represents surface material. The broken lines are for environmental purposes only and form no part of the claimed design.

1 Claim, 4 Drawing Sheets

FIG. 1

FIG. 2

FIG. 3

FIG. 4

FIG. 5
